UNITED STATES PATENT OFFICE.

LACEY Y. WILLIAMS AND FRANK B. HARRISON, OF TOLEDO, OHIO.

JOURNAL-BOX LID.

No. 851,850.

Specification of Letters Patent.

Patented April 30, 1907.

Application filed September 27, 1906. Serial No. 336,467.

To all whom it may concern:

Be it known that we, LACEY Y. WILLIAMS and FRANK B. HARRISON, citizens of the United States, residing at Toledo, in the county of Lucas and State of Ohio, have invented new and useful Improvements in Journal-Box Lids, of which the following is a specification.

The invention relates to car journal boxes, and in particular to the means for closing the opening at the end thereof through which oil and waste are introduced to and withdrawn from the interior of the box, the object being the provision of a double cover or two lids which shall effectively prevent the admission of dust and dirt to the journal and its bearings.

The invention consists in certain novelties of constructions and combinations of parts hereinafter set forth and claimed.

The accompanying drawings illustrate an example of the physical embodiment of the invention constructed according to the best mode we have so far devised for the practical application of the principle.

Figure 1 is an end view of a journal box in elevation showing the lids closed and part of the outer lid broken away to disclose the spring and part of the inner lid. Fig. 2 is a section on line $x-x$ of Fig. 1. Fig. 3 shows the relative position of one of the slots in the side flanges of the outer lid to the bolt when the lid is closed. Fig. 4 shows the position of the slot relative to the bolt when the outer lid is partly open. Fig. 5 shows one of the hinges of the inner lid. Fig. 6 illustrates the sleeve which is located upon the bolt and which operates the inner lid.

Referring to the several figures, the numeral 1 designates the journal box which may be of any type, said box having an opening at the end as shown; 2, a recess in the edge of the metal bounding the opening within which the edge of the inner lid fits when closed; 3, perforated cam lugs at the top edge of the opening; 4, the front straight and plain surface of the lug; 5, the rear straight and plain surface; 6, the top curved surface of the lug which constitutes a cam surface; 7, the concave surface between the lugs and adjacent the top edge of the opening; 8, the outer lid; 9, the bottom flange thereof; 10, the side flanges; 11, bosses upon the side flanges; 12, slots through the bosses; 13, the curved top edge of the lid; 14, a recess in the

top part of the lid formed in casting or by striking up the metal between dies; 15, two cam-shaped lugs upon the inner surface of the lid and which engage the surfaces of the cam lugs 3, 3, at the top edge of the box 60 opening; 16, two trunnions or bearings upon the inner surface of the lid for the support of the coils of a spring; 17, the inner lid; 18, the hinges for the inner lid, each secured at one end to the lid by rivets and the opposite 65 end formed with a hole or opening therethrough; 19, a recess in the opening; 20, a lug which the top edge of the outer lid is adapted to engage when it is raised; 21, the middle curved part of a hinge; 22, the longitudinally perforated sleeve; 23, the top lug on the sleeve; 24, two lugs at the ends of the sleeve; 25, a U-shaped spring; 26, the arms or branches thereof; 27, two coils in the branches or arms adjacent their ends; 28, 70 the free ends of the spring which bear against the inner surface of the outer lid; 29, the loop end of the spring; and 30 is the bolt about which the two lids turn.

The location of the several parts and elements when both the lids are closed is clearly shown by Figs. 1, 2, and 3. The bolt 30 passes through the slots in the side flanges of the outer lid, the holes in the cam lugs at the top edge of the box end opening, the openings in the hinges of the inner lid, and through the longitudinal passage in the sleeve. The cam lugs 15 on the outer lid engage the cam lugs 3 as shown. The free ends of the spring bear against the inner surface 80 of the cover and the coils 27 encircle the bearings 16. The loop end 29 of the spring engages the top lug 23 on the sleeve, and the lugs 24 at the ends of the sleeve are located within the recesses 19 in the surfaces bounding the holes through the ends of the hinges which support the inner lid. The sleeve with the top lug 23 and the hinges 18 constitute a lever mechanism and the bolt 30 serves as a fulcrum therefor.

By reference to Fig. 3 it will be observed that the bolt 30 is located at one side of the center of the slot 12 in the flange of the outer lid which is due to the fact that the spring 25 forces the outer lid into frictional contact 105 with the edge of the opening at the end of the box, while at the same time the loop 29 of the spring engaging the lug 23 on the sleeve forces the inner lid to its seat.

When the outer lid is partially opened, as 110

shown in Fig. 4, the cam lugs 15 travel up the surfaces 4 upon the cam lugs 3, over the curved surfaces 6, and against the pressure of the spring 25 which causes an outward movement of the outer lid so the relative positions of the slots 12 to the bolt 30 are as shown in the said Fig. 4. As the outer lid is further rotated about the bolt 30, the top curved edge of the lid engages the lugs 20 upon the hinges of the inner lid and forces it from its seat. When the cam lugs 15 have traveled over the surfaces 6 and bear against the straight plain surfaces 5 upon the lugs 3 the outer and inner lids are held in open positions as is obvious.

From the foregoing description taken in connection with the drawings it is clear we have produced a journal box having two lids which effectively exclude dust and dirt and thereby attains the object set forth as the end of our invention.

What we claim is:

1. The combination with a journal box having an opening at the end and cam lugs adjacent the edge of the opening, of an outer lid provided with lugs upon its inner surface to engage the cam lugs of the box; an inner lid provided with a lever mechanism; means for pivoting the two lids; and a spring secured to the outer lid and adapted to operate the lever mechanism of the inner lid and also force both lids to their seats.

2. The combination with a journal box having an opening and perforated lugs at the edge of the opening, of an outer lid having flanges with slots therethrough, and lugs upon its inner surface; a bolt passed through the lugs of the box and the slots of the outer lid; an inner lid; and a spring in connection with both the lids for holding the same to their seats.

3. The combination with a journal box having an opening and perforated cam lugs adjacent the opening, of an outer lid having side flanges with slots, lugs upon its inner surface, and trunnions upon its inner surface; an inner lid with hinges each provided at one end with an opening and a recess therein; a perforated sleeve with three lugs; a bolt; and a spring having coils located upon the aforesaid trunnions and its loop end engaging one of the lugs upon the sleeve.

4. The combination with a journal box having an opening and perforated lugs at the edge of the opening, of an outer lid having flanges with slots therethrough, and a recess within the body thereof; a spring secured within the recess of the lid; a bolt passed through the lugs of the box and the slots in the flanges of the lid; an inner lid; and means in connection with the inner lid adapted to be engaged by the spring.

5. The combination with a journal box having an opening and perforated cam lugs, of an outer lid having flanges with slots, cam

lugs, and a recess within the body thereof; a spring secured within the recess of the lid; a bolt passed through the cam lugs of the box and the slots in the flanges of the lid; an inner lid; and means in connection with the inner lid adapted to be engaged by the spring.

6. The combination with a journal box having an opening and perforated cam lugs, of an outer lid with perforated flanges, a recess, and cam lugs; a spring secured within the recess of the lid; a bolt; an inner lid; and means in connection with the bolt adapted to be engaged by the spring.

7. The combination with a journal box having an opening, of two lids; means for pivoting the lids at the edge of the opening; a U-shaped spring secured to the inner surface of the outer lid; and means in connection with the inner lid to engage the spring.

8. The combination with a journal box having an opening, of an outer lid and an inner lid; means for pivoting the lids to the edge of the opening; a U-shaped spring having coils near its ends located upon trunnions which are at the inner surface of the outer lid, and a loop end; and means in connection with the inner lid adapted to be engaged by the said loop end of the spring.

9. The combination with a journal box having an opening, of an outer lid with a curved top edge; an inner lid with hinges having lugs adapted to be engaged by the top edge of the outer lid when opened; and a bolt for pivoting the lids to the box.

10. The combination with a journal box having an opening, of outer and inner lids; and means for hinging the lids to the edge of the opening; the top edge of the outer lid being adapted to engage and open said inner lid when the outer lid is swung upon its hinge.

11. The combination with a journal box having an opening and perforated lugs, of an outer lid with a recess in the body thereof, and fixed cam lugs; a spring within said recess for forcing the outer lid to its seat; an inner lid; and means for pivoting the outer lid to the lugs upon the box.

12. The combination with a journal box having an opening, of an outer lid; an inner lid; means for pivoting the lids to the edge of the opening; and a spring in positive engagement with both lids which forces them to their seats.

13. The combination with a journal box having an opening and perforated lugs, of an outer lid with flanges provided with slots; an inner lid; a bolt for pivoting the outer lid to the box lugs; and a spring in connection with both lids which forces them to their seats; cam mechanism being provided between the outer lid and the box lugs.

14. The combination with a journal box having an opening, of two lids; means for

hinging the lids to the box; and spring mechanism upon the inner surface of the outer lid and positively engaging each lid and forcing both lids to their seats.

5 15. The combination with a journal box having an opening, of an outer lid provided with a recess in the body thereof; an inner lid; means for hinging the lids to the box; and a spring secured within the recess of the

outer lid and positively engaging both lids to and forcing the same to their seats.

In testimony whereof we affix our signatures in presence of two witnesses.

LACEY Y. WILLIAMS.
FRANK B. HARRISON.
